UNITED STATES PATENT OFFICE

2,086,144

WEB CHANGE DEVICE

Henry A. Wise Wood, New York, N. Y., assignor to
 Wood Newspaper Machinery Corporation, New
 York, N. Y., a corporation of Virginia

Application February 25, 1932, Serial No. 595,059
 Renewed December 7, 1936

4 Claims. (Cl. 242—58)

This invention relates to the supporting and manipulating of the running and fresh web rolls and of the running web for the purpose of splicing the running web to the fresh roll.

5 The principal objects of the invention are to provide for supporting the rolls in a position in which, during the splicing operation, they are stationary, and in some cases are stationary at all times; to provide convenient means where-
 10 by the rolls can be located in proper position for the splicing and running of the web, and in which the fresh roll can be rotated on its own axis up to web speed, so that there will be no necessity for slowing down the press when the
 15 splicing is to take place; to provide for so manipulating the web that it can be run from one and then from another roll conveniently without necessarily moving the rolls; and to provide means by which the loading of the new rolls is facilitated and the floor space demanded for rotating the rolls and supporting them while the
 20 splice is made will be reduced to a minimum, so that each roll supporting device can be placed within the over-all dimensions of a single unit of the modern type unit press.

25 Other objects and advantages of the invention will appear hereinafter.

Reference is to be had to the accompanying drawing, in which

30 Fig. 1 is an end view of a roll supporting and loading device constituting a preferred embodiment of the invention;

Fig. 2 is an elevation of the same, and

35 Fig. 3 is an enlarged sectional view on the line 3—3 of Fig. 2.

It is now well known that in the modern type high-speed newspaper printing press the splicing of the running web to the fresh web roll is done automatically without decreasing the speed 40 of the press, because the fresh roll can be rotated on its own axis up to web speed, and the splicing can be done at that speed. This invention relates particularly to the manner in which the rolls and web are manipulated and supported 45 before and after splicing.

The running roll R and the fresh roll R' are carried by a pair of pedestals 10 secured to the floor of the building so as to provide a strong and rigid mounting for the rolls. The rolls are 50 supported in these pedestals by means of blocks 11 mounted to move vertically in T-shaped guides or runways 12 formed in the pedestals themselves. Each block carries a rotatable chuck 13 adapted to fit in the end of the paper roll

and thus providing a rotatable mounting for the roll.

On the outer side of each block is a half internal screw thread or nut 14. Meshing with these nuts are a pair of vertical screws 15 mounted in the pedestals. These screws are rotated from a shaft 16 operated in any desired way through bevel gears 17.

In Fig. 1 the running roll R is shown nearly exhausted and the fresh roll R' is shown in position almost ready for splicing. Also another new roll R² is shown in position ready to be raised into the position of the roll R' after the splice is to be made.

The roll R² is located on a saddle 20 which is fixed at the top of a slide 21 having a rack 22 thereon. A pinion 23 operated from any desired source of power, meshes with the rack and can move the saddle downwardly at an inclination to any desired point, so that the roll R² can be placed on it conveniently from a truck on the floor. Rotating in the opposite direction the pinion will raise the saddle and the roll upwardly at an inclination, the slide being provided with guides operating in inclined tracks 24 carried by projections 25 on the pedestals.

The blocks 11 carrying the rotatable chucks 13 are put in place at the top of the pedestals so as to bring the chucks into the central passages in a new roll so as to mount it on the pedestal. After the roll moves down to running position and the roll is exhausted its blocks 11 can be lifted out through cut-outs 26 in the pedestals and placed at the top. Of course two sets of blocks are employed. Each of the chucks in the blocks 11 is slightly retractable so that the blocks can be taken out and replaced.

A shaft 30, which is connected with the printing press and consequently driven in proportion to the speed of the press, drives a shaft 31 by means of a belt through a clutch (not shown). On this shaft is pivoted a frame 32 which can be raised or lowered. This frame carries a series of pulleys on which run belts 27. The pulleys and belts are operated when the clutch is thrown in.

The operation of splicing the web is very simple. After the roll R' is put in place, as shown in Fig. 1, and the roll R is nearly exhausted, a normally inactive but preferably press-driven system of belts 27, or other means, is brought down into contact with the surface of the roll R' and operated to bring the roll up to web speed at its circumference. The web W from the roll R is caused by the position of the latter and a

guide roll 28, to pass close to the surface of the roll R' when the roll R is nearly exhausted. Now a deflecting means, shown in the form of a brush 29 is pressed against the web to force it against the roll R', the latter having previously been provided with spots of adhesive, or the roll R' can be lowered by means of the screws 15. In either case the web and the roll contact and the brush 29 backs up the web. The splice is completed, as is well understood in this art, and the web is cut off from the web R by means, not shown. This stub is then removed as stated, and the roll R' is moved downwardly to running position. After this the roll R² is mounted at the top of the pedestals where it is left in stationary position until the running roll is nearly exhausted, when this operation is repeated.

It will be seen that the fresh roll R' can be rotated up to web speed by the normally inactive means 27, preferably operated from a shaft of the press at such a speed that the belts of which it is composed will run at the speed of the web being drawn into the press. It will also be seen that a comparatively small floor space is required, reducing the demand for room which is very great, as high speed presses are used only in the largest cities where floor space is at a premium.

Although I have illustrated and described one form of the invention, I am aware of the fact that changes can be made therein by any person skilled in the art without departing from the scope of the invention as expressed in the claims. Therefore I do not wish to be limited to the exact form shown, but what I do claim is:—

35 1. In an apparatus of the character described, the combination of a vertical supporting means for the web rolls, blocks carried thereby for supporting the rolls, said blocks being movable downwardly in the support, a loading means comprising a saddle, a slide on which the saddle is fixed, said slide being provided with means for guiding

it to move at an inclination, means for moving the slide into such position that a roll of paper supported on the saddle will be brought into a position at the top of the roll support to serve as a fresh web roll, and normally inactive but press-driven means for rotating the roll when in that position to bring its surface up to web speed.

2. In an apparatus of the character described, the combination of a vertical supporting means for the web rolls, blocks carried thereby for supporting the rolls, said blocks being movable downwardly in the support, a loading means comprising a saddle, a slide on which the saddle is fixed, said slide being provided with means for guiding it to move at an inclination, and means for moving the slide into such position that a roll of paper supported on the saddle will be brought into a position at the top of the roll support to serve as a fresh web roll.

3. In an apparatus of the character described, the combination of a supporting means for the web rolls, a loading means comprising a saddle, a slide on which the saddle is fixed, said slide being provided with means for guiding it to move at an inclination, means for moving the slide into such position that a roll of paper supported on the saddle will be brought into a position at the top of the roll support to serve as a fresh web roll, and normally inactive but press-driven means for rotating the roll when in that position to bring its surface up to web speed.

4. In an apparatus of the character described, the combination of inclined tracks, a slide guided thereby, a saddle carried by the slide for supporting a web roll thereon and thereabove, means for raising the slide and saddle along said tracks to place the web roll in position for splicing, and means for lowering the web roll vertically after splicing into running position.

HENRY A. WISE WOOD.
